UNITED STATES PATENT OFFICE.

GEORGE RENTON, OF BOSTON, ASSIGNOR TO CHARLES H. ISBURGH, OF MELROSE, MASSACHUSETTS.

IMPROVEMENT IN HARNESS.

Specification forming part of Letters Patent No. **138,530**, dated May 6, 1873; application filed March 14, 1873.

To all whom it may concern:

Be it known that I, GEORGE RENTON, of Boston, in the county of Suffolk and State of Massachusetts, have invented certain Improvements in Harness, of which the following is a specification:

In the case of this invention, which refers entirely to a double harness, a single-harness breast-plate is used, and the collar and hames are dispensed with. The nature of the invention is fully described below.

In the accompanying drawing, Figure 1 is a view of a portion of a harness embodying my invention, in perspective. Fig. 2 is a side elevation of the device, particularly referred to below, detached from the remainder of the harness. Fig. 3 is a plan of the same.

Similar letters of reference indicate corresponding parts.

a is the breast-plate as used in single harness, but here represented as being used in double harness. *b* is the neck-strap. *c* is the strap which runs back to the check-rein hook. All these three straps are in the ordinary positions. *d* *d'* *d''* *d'''* *d''''* are different parts of a device by means of which the single-harness breast-plate can be used in double harness, the collar and hames being done away with. The parts *d'* *d''* *d'''* *d''''* are in one piece. The part *d* is for the accommodation of the yoke-strap, which passes through it. The link *d* is at liberty to turn in any direction, it being a swivel turning upon the pin or neck *d'*,

which connects the parts or links *d* and *d''* together. The part *d''* accommodates an extra strap, *e*, which passes through it, attaching on either side to the breast-plate *a*. By means of this strap *e* the breast-plate *a* and link *d''* are indirectly connected. *d'''* is the part or link through which passes an extra strap, *g*, passing from the said link *d'''* to the neck-strap *b* and back. The martingale is intended to pass down from the part or link *d'''*.

This device *d* *d'* *d''* *d'''* *d''''* is represented in the drawing as larger, and consequently more prominent, than it is in actual use, and is metallic, and usually silver-plated. While it is not conspicuous, it will be rather an ornament than otherwise.

This arrangement, dispensing with the collar and hames, will present a neater appearance than the old method, besides being a saving of expense, inasmuch as a single-harness breast-plate may be used in a double harness.

Having thus fully described my invention, what I claim, and desire to secure by Letters Patent, is—

The device shown and described, and consisting of the parts *d* *d'* *d''* *d'''* *d''''*, constructed, arranged, and operating substantially as and for the purposes hereinbefore set forth.

GEORGE RENTON.
